UNITED STATES PATENT OFFICE.

PYRMA E. FISCHER, OF NEW YORK, N. Y.

POT, PAN, AND KETTLE CLEANER.

1,179,297.

Specification of Letters Patent. Patented Apr. 11, 1916.

Application filed March 26, 1915. Serial No. 17,266.

To all whom it may concern:

Be it known that I, PYRMA E. FISCHER, a subject of the King of Great Britain, residing at New York, in the county of New 5 York and the State of New York, have invented a new and useful Improvement in Pot, Pan, and Kettle Cleaners, of which the following is a specification.

This invention relates to an inexpensive, 10 durable, efficient and sanitary cleaner for pots, pans, kettles and other like utensils.

The invention consists of the novel features of construction hereinafter described, pointed out in the claim and shown in the 15 accompanying drawings, in which:—

Figure 1 is a side elevation. Fig. 2 is a sectional elevation. Fig. 3 is a horizontal section, a clamping ring being shown in plan. Fig. 4 is an enlarged detail view of a 20 portion of the cleaning fabric.

In constructing the device I employ a cup of any suitable material, preferably metal, and which is provided with an interiorly extending bead 2 adjacent its top, the rim 25 portion of the cup above said bead being curved inwardly as shown at 3. A handle 4 has its standard 5 secured to the bottom of the cup, the handle being arranged centrally above the cup. A suitable cleaning 30 fabric envelops the cup and folds over the rim portion 3 and a part of the bead 2. A split, spring clamping ring 7 having upturned portions 8 fits within the cup and bears on the bead 2, clamping the fabric 35 between the rim portion of the cup and said

bead, and securely holding it in place. The ring is fitted into and removed from position by pressing the upturned end portions together thereby reducing the diameter of the ring. By having the rim portion curved 40 inwardly the cup is slightly reduced in diameter at the top, and accidental displacement of the clamping ring prevented.

While any suitable fabric may be employed I prefer to use a cloth having heavy 45 intersecting strands to which is stitched or otherwise secured a metal strip, cord or the like which is arranged upon the cloth in a spiral coil, as indicated in Fig. 4. The cleaning fabric can be easily removed for 50 washing, or for the purpose of inserting a new cloth in position.

What I claim is:—

The combination with a cleaning fabric, 55 of a cup adapted to be enveloped therein, said cup having an upwardly projecting and centrally arranged handle, supported from the bottom of the cup, and having an interior bead, and an inwardly curving rim portion, the fabric overlapping said rim portion when in position, and a split spring 60 clamping ring, having upturned end portions, said ring when in position being locked between the bead and the inwardly curving portion of the rim, and gripping 65 the overlapping portion of the fabric.

PYRMA E. FISCHER.
